US00D475099S

(12) **United States Design Patent** (10) Patent No.: **US D475,099 S**
Manville (45) Date of Patent: **** May 27, 2003**

- (54) **CRAFT KIT CONSTRUCTION COMPONENT-ARM AND HAND FORM WITH THROUGH-HOLE**
- (75) Inventor: **Richard B. Manville**, Los Angeles, CA (US)
- (73) Assignee: **Mattel, Inc.**, El Segundo, CA (US)
- (**) Term: **14 Years**
- (21) Appl. No.: **29/157,909**
- (22) Filed: **Mar. 26, 2002**
- (51) LOC (7) Cl. **21-01**
- (52) U.S. Cl. **D21/658**
- (58) Field of Search D21/658, 621-649, D21/587, 593, 594, 589; 446/97-101, 390, 387, 388, 268, 376, 379, 340, 382, 336, 354, 359, 362, 363
